UNITED STATES PATENT OFFICE.

HOWARD S. KNEEDLER, OF PHILADELPHIA, PENNSYLVANIA.

DESIGN FOR TICKING OR SIMILAR FABRICS.

SPECIFICATION forming part of Design No. 17,574, dated August 2, 1887.

Application filed July 5, 1887. Serial No. 243,450. Term of patent 7 years.

To all whom it may concern:

Be it known that I, HOWARD S. KNEEDLER, a citizen of the United States, and a resident of Philadelphia, Pennsylvania, have invented a new and original Design for Ticking or Similar Woven Fabrics, (Case X,) of which the following is a specification.

My design for ticking or other woven fabrics is fully illustrated in the accompanying drawings, in which--

Figure 1 is a view showing the ground effect, and Fig. 2 is a view drawn to a larger scale and showing the details of the stripes.

My design comprises two styles of stripes, A and B, alternating with each other on a ground color, G.

The stripe A comprises a central bar, a, bordered on each side by a dark stripe, 1, followed by stripes 2 3 4, lighter in shade toward the ground.

The stripe B comprises a central light bar, b, having running through it two narrow dark

lines, b'. On each side of the central bar, b, are stripes 5, gradually increasing in shade until a light stripe, 6, is reached. The bar B 25 has a dark border-stripe, 7, on each side.

I claim--

The design for ticking or other woven fabrics, comprising alternating stripes A and B on a ground, G, the stripe A consisting of a central bar, a, bordered by dark bars 1 and shaded stripes 2 3 4, while the stripe B consists of a central light bar, b, with two dark lines and bordered by shading-stripes 5, light stripes 6, and dark border-stripes 7, all substantially as shown and set forth. 30 35

In testimony whereof I have signed my name to this specification in the presence of two subscribing witnesses.

HOWARD S. KNEEDLER.
